Patented Aug. 22, 1916.

UNITED STATES PATENT OFFICE.

ALEXANDER DOMBROWSKY, OF BALBOA, CANAL ZONE.

STRETCHER.

1,195,789.

Specification of Letters Patent. Patented Aug. 22, 1916.

Application filed October 29, 1915. Serial No. 58,669.

To all whom it may concern:

Be it known that I, ALEXANDER DOMBROWSKY, a citizen of the United States, and a resident of Balboa, Canal Zone, Panama, 5 have invented a new and useful Improvement in Stretchers, of which the following is a specification.

My invention is an improvement in stretchers of the character used for stretching and creasing trousers, wherein a frame is provided for engaging the opposite side edges of the superposed legs of the trousers, together with means connected with the frame and movable with respect thereto for 15 clamping the frame on the said edges, the frame being adjustable for varying sizes of trousers and arranged to permit the frame to be hung up to support the trousers.

In the drawings:—Figure 1 is a front 20 view of the improved stretcher, Fig. 2 is an edge view, Fig. 3 is an enlarged partial front view of a portion of the frame showing the hinge construction, and Fig. 4 is a section on the line 4—4 of Fig. 3, looking in 25 the direction of the arrows adjacent to the line.

The present embodiment of the invention is an improvement over my prior Patent #1,004,390, granted Sept. 26, 1911, and 30 comprises a supporting bracket, formed of wire or the like, bent to form a supporting eye 1, and arms 2 depending from the eye, each arm having at its lower end an outwardly bent portion 3, having at its free 35 end an inwardly bent journal pin 4. Each journal pin is provided at its inner end with a lateral lug 5 for a purpose to be presently described, and a loop 6 of wire or the like, encircles the depending portion 2 at the 40 junction thereof with the outwardly bent portion 3.

The eye 1 is formed from two coils, and the portions 2 extend from the ends of the wire after it has been bent into the coils. A 45 pair of sectional clamping bars is connected with each journal pin 4, being journaled thereon, and each pair of clamping bars consists of front and rear members, each member being sectional. Each pair of 50 clamping bars consists of upper sections 7, and lower sections 8, connected to the upper sections by the hinge joint shown more particularly in Fig. 3. This hinge is composed of an upper leaf 9, secured to the lower end 55 of the section 7, and a lower leaf 10 secured to the upper end of the section 8, the said

leaves being secured to the sections by means of screws 11 or the like. The hinge leaves 9 and 10 have alined bearings 12 at their meeting edges for receiving a pintle, and 60 the bearings are omitted at the center to form a notch for receiving the coil 13 of a spring, the said coil encircling the pintle.

The ends 14 of the coil are bent in opposite directions to engage beneath bearing 65 sleeves 15 on the hinge leaves 9 and 10. The arrangement of the hinges 9 and 10 is such that when the sections 8 are released from the resilient clamping mechanism to be later described, they will take the position indicated in dotted lines in Fig. 2, that is, the spring hinges will swing the sections 70 away from each other.

A suspending yoke is provided for connecting each pair of bars with the adjacent 75 journal pin. Each of the hanging yokes comprises a body 16 in the form of an open loop engaging the adjacent journal pin 4, and depending arms 17, which are lapped upon the outer faces of the adjacent clamping 80 bar sections 7, and secured thereto in any suitable or desired manner.

Mechanism is provided for clamping the members of each pair of bars together on the trousers indicated at 18. The said 85 clamping mechanism is shown more particularly in Figs. 3 and 4, and each of the said mechanisms is formed from wire of suitable gage, bent to shape. Each clamping mechanism comprises an eye 19, and arms 20 and 21, extending from the eye in parallel spaced 90 relation, one of the arms 20 in the present instance having an outwardly bent lug 22, forming a finger piece for operating the clamping mechanism, and the other arm 21 95 of each clamping mechanism has a portion 23 extending at an acute angle with respect to the portion 21, and having at its free end an eye 24.

Each clamping mechanism is hinged or 100 pivoted to a bar section 7 or 8 of the rear member of each pair by means of a screw 25 passing through the eye 24, and the arms 20 and 21 which normally tend to move toward each other are adapted to engage the 105 outer faces of adjacent sections 7 or 8 as the case may be, to press the said sections toward each other.

An adjusting bar 26 is arranged between the sections 8 of the rear members of the 110 pairs, the said bar being pivoted to the section 8 of one pair by means of the screws

25, and at its other end the lower edge of the bar is provided with notches 27 for engaging a pin 28 on the adjacent section of the rear member of the other pair.

5 In practice, the clamping members, which are four in number for each pair of bars, are pivoted to swing outwardly into inoperative position or inwardly into operative position, and the outwardly bent lug 22 10 of each clamping member assists in guiding the arms 20 and 21 to proper position. When the clamping members of the lower section 8 of either pair of bars are swung outwardly, the spring hinges 9 and 10 will 15 move the sections into the dotted line position of Fig. 2, thus facilitating the introduction of the trousers into the stretchers.

In use, the clamping mechanisms are disengaged, and after the trousers have been 20 arranged as shown in Fig. 1 with the legs carefully superimposed upon each other, and with the side edges of the legs in register, one edge of the superimposed legs is introduced between one of the pairs of 25 bars and during this operation the stretcher may be suspended from a hook or the like, by means of the eye 1. After the superimposed edges of the trousers have been inserted in between the pair of clamping bars 30 the clamping devices of the upper section 7 of the pair are placed in operative position, thus clamping the upper sections 7 on the superimposed edges. The upper sections of the other pair may then be placed 35 or the lower sections of the first-named pair may be placed as may be desired.

In the first-named instance after the clamping members of the upper sections of the other pair of bars have been clamped on 40 the sections, then the lower sections of the first-named pair are pressed together and connected by the clamping members. The lower sections of the other pair are then placed, and the adjusting or extension bar 45 26 is made use of to press the pairs of clamping bars away from each other to stretch the trousers legs laterally. When a sufficient degree of tension has been attained the pin 28 is engaged with the adjacent 50 notch 27, and the trousers are properly held to stretch and crease them. To release the trousers it is only necessary to disengage the clamping members and the extension or adjusting bar. The disengaging process 55 will commence with the clamping bars at the bottom while during the placing of the trousers the clamping mechanisms will be engaged from the top downward.

It will be noticed that one pair of clamping bars is of greater length than the other, the sections 7 of the said pair being longer 60 than the sections 7 of the other pair as are also the sections 8 of the first-named pair. When the clamping mechanisms are swung outwardly as indicated in dotted lines in 65

Fig. 3 the clamping arms 20 and 21 are moved entirely out of engagement with the clamping bars so that the said mechanisms offer no impediment to the insertion of the trousers. The pressure of the clamping bars 70 toward each other by the clamping mechanisms insures the proper creasing of the trousers, and the use of the extension bar 20 insures the proper stretching.

I claim:—

1. A trousers stretcher and creaser substantially as herein described, comprising a plurality of pairs of clamping bars, the members of each pair being adapted to engage the side edges of the superposed legs from the bottom to near the top, a suspending bracket to which the pairs are pivoted in spaced relation, a series of resilient clamps pivotally connected with each pair of bars and arranged in spaced relation to swing 85 outwardly into inoperative position to release the members of the pair and to swing inwardly to clamp the members together on the trousers, each bar being sectional, and a spring hinge connecting the sections of each 90 bar to cause the lower sections to swing outwardly when released from the clamping mechanisms, and an extension bar pivoted to the lower section of one member of one pair and having an adjustable connection with 95 the adjacent section of the adjacent member of the other pair.

2. A trousers stretcher and creaser substantially as herein described, comprising a plurality of pairs of clamping bars, the 100 members of each pair being adapted to engage the side edges of the superposed legs from the bottom to near the top, a suspending bracket to which the pairs are pivoted in spaced relation, a series of resilient clamps 105 pivotally connected with each pair of bars and arranged in spaced relation to swing outwardly into inoperative position to release the members of the pair and to swing inwardly to clamp the members together on the trousers, each bar being sectional, and a spring hinge connecting the sections of each bar to cause the lower sections to swing outwardly when released from the clamping mechanisms.

3. A trousers stretcher and creaser, comprising a plurality of pairs of sectional clamping bars, a common support to which the members of each pair are pivoted, said bars being spaced apart from each other to 120 clamp the opposite side edges of the superposed legs of a pair of trousers, clamping mechanism for clamping the members of each pair together on the legs, and a spring hinge connecting the sections of each bar and 125 mounted to swing the lower section outwardly away from the adjacent lower section.

4. A trousers stretcher and creaser comprising clamping members formed of sec- 130

tions, the sections at one end of the members being connected together, and the sections at the other end being free and disconnected from each other, means connecting the sections of each member and normally tending to move the free or disconnected sections laterally to facilitate placing the trousers between coacting sections of complementary clamping members, and means pressing the clamping members together to cause them to grip the trousers placed between them.

ALEXANDER DOMBROWSKY.
